K. W. LARKIN

AUTOMATIC AIR MOISTENER FOR HOT AIR FURNACES

Filed Dec. 19, 1925

INVENTOR.

KERN W. LARKIN

BY

Walter E. Whalen
ATTORNEY.

UNITED STATES PATENT OFFICE.

KERN WILLIAM LARKIN, OF DETROIT, MICHIGAN.

AUTOMATIC AIR MOISTENER FOR HOT-AIR FURNACES.

Application filed December 19, 1925. Serial No. 76,551.

This invention relates to automatic air moisteners for hot air furnaces and the object of the invention is to provide an air moistener consisting of a water pan adapted to be positioned in the hot air chamber of the furnace and in which the opening of the fire door of the furnace causes the pan to fill with water.

Another object of the invention is to provide a device of the character described in which the pan is filled with water during the period which the fire door is opened.

A further object of the invention is to provide a water pan containing a float valve for maintaining a water level in the water pan, the said float valve operating subsequent to opening of the fire door of the furnace which through a valve arrangement allows flow of water to the float valve.

These objects and the several novel features of the invention are hereinafter more fully described and claimed and the preferred form of construction by which these objects are attained is shown in the accompanying drawing in which—

Fig. 1 is a front elevation of a hot air furnace with my air moistener as utilized therewith.

Fig. 2 is an enlarged section through the air moistener showing its connection with the fire door of the furnace.

Fig. 3 is a plan view of the float operated valve within the water pan.

Fig. 4 is a section taken on line 4—4 of Fig. 3.

Fig. 5 is an enlarged section taken on line 5—5 of Fig. 2.

As shown in Fig. 1 the hot air furnace 1 is provided with a water pan 2. The end of this water pan extends from the front of the furnace to a slight extent and is usually provided with a cover extending outwardly from the front of the furnace. This pan extends inwardly into the hot air chamber 45 of the furnace and is open at the top within the furnace. The water pipe 3 for supplying water to the pan 2 is provided with a valve 4 therein as shown in Figs. 1 and 2. This valve is of a quick compression type and is provided with threads 5 so that when the valve is turned in either direction it may be quickly opened and closed. The valve 4 is provided with a round stem 6 having a square recess 7 to receive the squared end 8 of the rod 9. The rod 9 extends upwardly through the two lugs 10 and 11 which ex-

tend outwardly from the door frame of the furnace. This rod 9 forms the pivot for the fire door 12 which is provided with two lugs 13 and 14. The lug 13 is provided with a round aperture for the stem 9 while the lug 14 is provided with a square aperture. The upper end 15 of the stem 9 is squared as shown in Fig. 5 where it extends through the lug 14 and a screw 16 is threaded into this squared end as shown in Figs. 2 and 5. By this arrangement when the fire door is opened the rod 9 is turned therewith, thus opening the valve 4 and when the fire door is closed the valve 4 is closed. A pipe 17 leads from the outlet of the valve body into the water pan 2 and is provided with a float controlled valve on the end thereof within the pan. This valve comprises a float 18 having a stem 19 which is pivoted at 20 and a link 21 is pivoted at 22 to the end of the arm 19. This link is pivoted at 23 to an arm 24 which extends through the valve member 25 as shown in Figs. 3 and 4.

At the opposite end the arm 24 pivoted on the bolt 26 so that as the arm 24 is lowered the valve 27 on the valve member 25 closes the valve seat 28 to prevent further flow of water. As the float 18 falls due to evaporation of water from the pan 2, the end of the arm 19 is raised and through means of the link 21 the arm 24 is raised, thus lifting the valve 27 from its seat. When the valve 27 is opened as shown in Fig. 2 water will not flow into the pan 2 until the fire door 12 of the furnace is opened to open the valve 4. When this valve 4 is opened by opening the fire door the water will rush through the float valve and fill the pan 2 with water until the float valve is closed again by the movement of the float 18.

I am aware that there are other devices which utilize a float valve for filling the water pan in a hot air furnace. With these types the water lost by evaporation is replaced by fresh water through a float controlled valve but due to the slowness of evaporation the valve opens very slightly due to the slight change of float position which causes a trickle of water to flow into the pan continuously which soon pits the valve seat. When this occurs the float valve is useless as far as accurate control of the water level is concerned. The object of my invention is to provide an arrangement to overcome the defects of this type of construction. By providing a valve 4 controlled

by the furnace fire door which is always opened for firing the furnace at least once a day, the evaporation between operations of the valve 4 lowers the level in the pan to a considerable extent so that when the valve 4 is opened by the fire door the water flows in with a rush which quickly brings the water level to the proper height. Upon again closing the fire door the valve 4 is closed so that subsequent opening of the float control valve does not allow water to pass into the pan until the fire door is again opened. It will thus be readily seen that the float valve is usually wide open when the water is added to the pan by opening the fire door and thus the pitting of the valve seat by a trickling flow of water will not occur.

From the foregoing description it becomes evident that the device is very simple and efficient in operation, is automatic in that it requires no attention except that usually given in firing a furnace, will overcome the objections of previous devices of this type and provides a device which accomplishes the objects described.

Having thus fully described my invention, its utility and mode of operation, what I claim and desire to secure by Letters Patent of the United States is—

1. An automatic air moistener for hot air furnaces comprising a water pan open to the hot air chamber of the furnace, a pipe for supplying water to the pan, a valve in the said pipe, the valve having a stem provided with a squared recess, a rod having a squared end fitting in the said recess, the rod being secured to the furnace fire door and forming a pivot for the said door,

whereby, as the door is opened the valve is opened and as the door is closed the valve is closed and a float controlled valve on the end of the said pipe within the water pan.

2. An automatic air moistener for hot air furnaces comprising a water pan open to the hot air chamber of the furnace, a pipe for supplying water to the pan, a valve in the said pipe, the valve having a stem provided with a squared recess, a rod having a squared end fitting in the said recess, the rod being secured to the furnace fire door, whereby, as the door is opened the valve is opened and as the door is closed the valve is closed and a float controlled valve on the end of the said pipe within the water pan. 55

3. An automatic air moistener for hot air furnaces comprising a water pan open to the hot air chamber of the furnace, a pipe for supplying water to the water pan, a valve in the said pipe, a rod connected with the valve and secured to the furnace fire door, whereby, when the door is closed the valve is closed and when the door is opened the valve is opened and a float controlled valve on the end of the said pipe within the water 65 pan.

4. An automatic air moistener for hot air furnaces comprising a water pan open to the hot air chamber of the furnace, a pipe for supplying water to the water pan, a valve 70 in the said pipe connected for operation by the furnace door, the said valve being closed when the furnace door is closed and being opened when the furnace door is opened and a float controlled valve on the end of the 75 pipe within the water pan.

KERN WILLIAM LARKIN.
